UNITED STATES PATENT OFFICE.

ALBERT R. GOLDRICK, OF CLEVELAND, OHIO, ASSIGNOR TO MOTOR TERMINALS COMPANY, OF CLEVELAND, OHIO, A CORPORATION OF DELAWARE.

DEVICE FOR CONNECTING ELEVATING CABLES TO LOAD CARRIERS.

Application filed June 26, 1920. Serial No. 392,013.

To all whom it may concern:

Be it known that I, ALBERT R. GOLDRICK, a citizen of the United States, residing at Cleveland, in the county of Cuyahoga and 5 State of Ohio, have invented a certain new and useful Improvement in Devices for Connecting Elevating Cables to Load Carriers, of which the following is a full, clear, and exact description, reference being had 10 to the accompanying drawings.

This invention relates to devices adapted to lock a hoisting cradle with a load, for instance where the cable is to engage and lift the removable body of an automobile truck.

15 The methods heretofore practiced for engaging a hoisting cradle with a load made it necessary for an operator to manually engage the hoisting element with the load at each point of connection. These connecting points were often inaccessible, especially 20 where a loaded crate was placed upon a truck where one side of the crate would be adjacent to a raised platform and the other side would be adjacent to a street. This of course involved a great deal of time and 25 inconvenience on the part of the operator and caused the trucks to remain idle for a considerable length of time.

The essential object of my invention is 30 to provide engaging mechanism which may be operated from either side of a load and which will be adapted to operate simultaneously a plurality of connecting points. Further objects are to provide a mechanism 35 which will be capable of standing severe wear and tear incident to unprotected hoisting machinery, and to provide a mechanism which is capable of being cheaply manufactured. The above and other objects will be 40 come more apparent in the following description which relates to the drawings. The essential characteristics are set forth in the claims.

In the drawings Fig. 1 is a side elevation 45 of a hoisting cradle embodying the features of my invention and as shown is connected to a removable automobile body; Fig. 2 is a plan of the cradle with the accompanying mechanism; Figs. 3 and 4 are details in the 50 nature of sections of the engaging mechanism; Fig. 5 is an enlarged detail of a corner connection.

Designating the parts by the use of reference characters, 10 and 11 represent longitudinal beams, 12 and 13 transverse beams

which constitute a cradle or frame which may be supported at the corners thereof by cables 15, and adapted to lift portable crates or removable bodies 16. Suitable mechanism which will be hereinafter described is provided to engage the cradle with the portable 60 crate.

The longitudinal members 10 and 11 and the transverse members 13 and 14 of the fabricated frame may be channels which may 65 be secured together by castings 17, one of which is positioned at each corner of the frame. Rigidly secured to the centers of the longitudinal members is a transverse reinforcing member 18 which serves, in addition to strengthening the frame, to provide 70 a bearing plate for the levers 19 and a cross rail 20. The fabricated frame acts as a spacer to maintain a constant distance between the supporting cable and to support 75 the engaging mechanism.

The corner supporting members 17, preferably castings, may be rigidly secured to the frame by rivets and are provided with suitable apertures 21 for engaging the hoisting cables. The points to which the cables are secured to the castings are preferably 80 above the top plane of the frame. The bottom of the casting has an opening 22 adapted to receive the engaging hook 24, of the 85 removable body or crate 16. An extension 25 may be provided on the lower portion of the casting to serve as a bearing plate for a rod 26 slidably mounted therein. It will be seen that an upward stress exerted on the 90 hoisting cables is transmitted directly to the rod through the medium of the casting, while the frame merely serves as a spacer for these corner supporting members.

The mechanism which operates the engaging pins is as follows:—A rod 26 as 95 shown in Fig. 4 is slidably mounted in each of the four corner supporting members and is connected to the cross rail 20 by the links 27 and 28. These links are loosely connected, preferably by pins, to the cross rail at 29 and 30, thus forming a toggle joint. The cross rail 20 is slidably mounted on the transverse members 13 and 14 of the frame in bearings 29 and 30. The levers 105 19 pivotally mounted to the lower side of the reinforcing member 18 have their inner ends slidably connected at 31 to the cross rail 20, while the outer ends 32 protrude beyond the longitudinal members 10 and 11, 110

and forming a handle. Guide plates 33 are rigidly secured to the longitudinal members and are provided with a guide way or slot 34 in which the levers are adapted to move. 5 The spring 35, one end of which is secured to the transverse member 18 and the other end to the cross rail, tends to pull the cross rail to a position shown by the dotted lines in Fig. 2. The levers 19 are normally in 10 a position shown by the dotted lines, while the engaging pins 26 extend across the opening 22 in the casting 17.

Assuming that the frame is lowered and about to be ready to engage a crate, the operator, standing on either side of the crate, will throw the levers 19 into a position shown in full line in Fig. 2. This movement causes the cross rail to move to the right and simultaneously withdraws the engaging pins 26 from the outer bearing of the corner supporting members. The levers are held in this position until the frame is lowered over the grappling hooks of the crate, whereupon the levers are released and 25 the spring 35 forces the engaging pins back to their normal position. The load may then be lifted and safely transported.

Having thus described my invention, I claim:-

30 1. In a device of the class described, the combination with a frame of means for engaging a plurality of hoisting elements with a load and means projecting laterally from the frame for simultaneously operating the 35 said engaging means from either side of the load.

2. In a device of the class described, the combination with a frame depending from a plurality of hoisting cables arranged in 40 the form of a rectangle, of means operable in a substantially horizontal plane for engaging the hoisting elements with a load, and means for simultaneously operating the said engaging means from either side of 45 the load.

3. In a device of the class described, the combination with a substantially rectangular frame of laterally shiftable members mounted on said frame and adapted to engage a load, said members being operable 50 in a horizontal plane, and means for simultaneously moving said members into and out of engagement with the load.

4. In a load-locking device, the combination with a frame comprising longitudinal and transverse members, of brackets secured to the corners of the frame, each of said brackets having means at one end thereof for securing hoisting cables and each having 55 a downwardly facing recess at the other end thereof, means slidably mounted in said brackets and transversely of said recess for engaging a load, and means for operating the engaging means simultaneously from 60 either side of the load.

5. In a locking device, the combination with a frame having longitudinal and transverse channel-bar members of supporting members at each corner thereof, said members having one portion thereof adapted to hold hoisting cables, another portion thereof adapted to embrace engaging means on a load, means slidably mounted in the corner members for interlocking with the engaging members of the load, and means for simultaneously operating the said sliding means. 75

6. In a locking device, the combination with a frame, of corner supporting members adapted to hold a plurality of hoisting cables attached thereto, load engaging members slidably mounted in said corner supports, and levers adapted to be operated from either side of a load, whereby the said load engaging members may be simultaneously operated and means connecting 85 the levers with the members.

7. In a device of the class described, the combination with a fabricated frame, of corner supporting members adapted to support hoisting cables, bars slidably mounted in 90 said supports, horizontally shiftable levers adapted to simultaneously operate the said bars and links connecting the said bars with the said levers.

8. In a device of the class described, the combination with a frame having longitudinal and transverse beams and reinforcing beams connecting the centers of the longitudinal beams, corner supporting members rigidly secured to the frame, bars slidably 100 mounted in the corner members and adapted to engage a load, a cross rail adapted to connect the centers of the transverse members and slidably mounted thereon, means connecting the cross rail with the bars, and 105 means for simultaneously operating the bars.

9. In a device of the class described, the combination with a frame, comprising a fabrication of longitudinal and transverse 110 members with a reinforcing beam therein, of corner supporting members adapted to engage a plurality of hoisting cables, bars slidably mounted in said corner supports, a cross rail slidably mounted on the said 115 transverse frame members, links connecting the cross rail with the bars and levers pivotally mounted on said reinforcing beams for simultaneously operating the said bars.

10. In a device of the class described, the combination with a rectangular frame having longitudinal and transverse members and a reinforcing member connecting the centers of the longitudinal members, of corner supports, brackets mounted on the corners of said frames and adapted to support hoisting cables, bars slidably mounted in the said brackets, a cross rail connecting the centers of the said transverse members and 125 slidably mounted thereon, links connecting 130

the said bars with the cross rail, levers pivotally mounted on the said reinforcing members adapted to simultaneously operate said members from either side of the load, means 5 for limiting the movement of the levers and means for constantly urging the bars into engaging position.

11. In a locking device, the combination with a frame comprising a fabrication of 10 structural members, of corner supporting members adapted to hold a plurality of hoisting cables attached thereto, bars mounted in said members, levers adapted to be operated in a substantially horizontal plane 15 from either side of a load, whereby the said bars may be simultaneously operated and means connecting the levers with the bars.

12. In a device of the class described, the combination with a frame comprising a fabrication of longitudinal and transverse beams with a reinforcing beam therein, of corner members adapted to engage a plurality of hoisting cables, load engaging bars mounted on said transverse beams, a cross- 25 rail, links connecting said rail with the bars, and levers pivotally mounted on said reinforcing beams for simultaneously operating said bars to engage or release a load.

13. The combination with a load having a 30 substantially rectangular form and provided with four upwardly extending lifting members, of a rectangular member adapted to be lowered into engagement with said lift-

ing member and provided with positioning members cooperating therewith, laterally 35 shiftable bolts carried by the rectangular member near the corners thereof, and means for simultaneously moving said bolts transversely of said lifting members into position beneath their uppermost portions, 40 whereby the rectangular member becomes locked thereto.

14. In combination, a load, a member having a form substantially similar to the load, horizontally shiftable bars carried by said 45 member for engaging and locking a load, and a lever projecting laterally from the load and operable in a horizontal plane for moving said bars simultaneously into and out of engagement with a load. 50

15. The combination of a frame provided with downwardly facing recesses, and devices mounted on said frame, and adapted to extend across said recesses to engage beneath upwardly extending load-lifting members, which may occupy the recesses. 55

16. In a load-locking device, the combination with a frame of brackets secured to the frame, each of said brackets having a downwardly facing recess, means slidably mounted in said brackets and transversely of said recess for engaging a load, and means for operating the engaging means. 60

In testimony whereof, I hereunto affix my signature.

ALBERT R. GOLDRICK.
